A. J. TANNER

DISPLAY CONTAINER

Filed April 30, 1927

FIG. 1.

FIG. 2. 5

INVENTOR:
A. J. TANNER.

UNITED STATES PATENT OFFICE.

ARNOLD J. TANNER, OF NORTH HAVEN, CONNECTICUT.

DISPLAY CONTAINER.

Application filed April 30, 1927. Serial No. 187,788.

The invention hereinafter set forth relates to containers useful for packing and displaying merchandise, and one object of the invention, amongst others, is to provide an efficient and comparatively inexpensive container, which may be easily assembled for packing, and quickly set up for display and dispensing purposes.

One salient feature of the container forming the subject of this invention, is the provision of a display device or placard, which is permanently held in its erect position for display, consequently, when the dealer sets up the box for use, he is not required to perform any operation whatsoever to place the display member in the required position. With containers in general use, the display member thereof must be unfolded when the containers are set up, and besides the operation of setting up the display member, the construction is such that said member is not held rigidly in an erect position unless additional locking or retentive means are employed to hold the display member in the erected position.

Another feature of the present invention is the arrangement and construction of the container so that a pair of containers can be packed together as sections to form a single package. The construction of the improved container lends itself to such duplex packing, which packing is of particular advantage in such cases where it is desired to reduce the size of the container to be displayed. For example, in some trades it is an established practice to pack a certain number of articles in one package, and frequently the container thus packed is so large and bulky that it can not be conveniently displayed in a limited space. By dividing the package for display only, the custom of packing for sales purposes may be adhered to, but the dealer has the advantage that he can display the package in sections.

In carrying out an embodiment of the invention, the improved container comprises a receptacle, which may be constructed in any conventional way, so that it has an open top with front, back and side walls, and a bottom. According to this invention, the back wall is made considerably higher than the other walls, so as to provide a rigid, elevated display card, which is permanently held in an erect position, and which forms an integral part of the container or receptacle. The back wall may be single and in

which case it would be required to print both sides of the blank from which the container is constructed. To save the cost of double printing, the back wall is extended 60 still higher and doubled over so that the surface of the back of the wall is shown in front, thereby necessitating printing on one side only of the blank.

The invention will be fully described hereinafter with reference to the accompanying drawings, wherein:—

Figure 1 is an elevation showing two container sections positioned so that they can be brought together to form a single package, and

Figure 2 is a plan view showing the blank of which the container sections are constructed.

Referring to said drawings, the blank of 75 which the container sections are composed, is cut in the shape and size, according to requirements. The blank is cut and scored so as to divide the blank into a number of portions as follows: *a*, forming the back wall 80 of the receptacle; *b*, the front wall; *c*, the end or side walls; *d*, the folding over portion of the back wall, and *e* forms the bottom of the receptacle. The blank also has side tongues 1 in pairs and folding over locking tongues 2 at each end, and which latter tongues are slightly expanded at the ends 3 for the purpose hereinafter set forth. The front wall *b* of the receptacle is cut away at 4 so as to better expose the contents and to facilitate the packing and removal of the same.

It is a comparatively simple matter to erect the box from the blank, as designed and shown in the drawing, for it is only required to bend the portions *a*, *b*, and *c* at right angles. The side tongues 1 are then folded inwardly and the locking tongues 2 are folded inwardly over the side tongues 1, and the expanded ends 3 of the locking tongues 2 will engage the erected side walls with a binding effect, thereby retaining the receptacle in its set up condition. The extended end of the container back wall, is then doubled over and the ends 5 are also expanded so as to bind against the side walls of the receptacle. The said back wall preferably has a cut-out portion 6 so as to increase the height of the display card without using additional stock. Further it will be noted that only the exposed surfaces of the container are printed and which printing is

represented by shading on the container and blank illustrated in the drawing.

The container sections are packed in the usual way after they are erected and to form a single package, the two containers are nested together, so that the top 7 of one receptacle will abut against the top of the other receptacle and the display back or placard of one container will lap over the front of the other container. To hold the package together, an outer sliding sleeve 8 is slipped over the two container sections when together, and thereby a rigid and firm shipping package is provided.

15 I claim—

1. A container for merchandise composed of a pair of separate packing units, each unit having front, side and back walls, said units both having an open top, the back wall of one unit extending above said side walls and arranged to stand constantly in a relatively upright position, means for uniting said units to form a single package and when so united said units lying with the open tops thereof together and said extended back of one unit overlapping the other unit.

2. A packing and display container for

merchandise composed of a pair of separate units, each unit having an open top, side walls, a back wall, a front wall with an opening therein, the back walls of both units extending above the side walls and arranged to stand constantly in a relatively upright position, means for uniting said units to form a single package and when so united said extended back wall of one unit operating as a cover for the open front wall of the other unit.

3. A packing and display container for merchandise composed of a plurality of companion units, each unit having an open top, side walls, a back wall and a front wall with an opening therein, a display card extending from the back wall of one unit, and said card being arranged to stand constantly in a relatively upright position, means for uniting said units to form a single package and when so united said display card covering the opening in the front wall of a companion unit.

Signed at New Haven, county of New Haven, State of Connecticut, this 29th day of April, 1927.

ARNOLD J. TANNER.
